United States Patent Office

Des. 211,655

Patented July 9, 1968

211,655

PLATE OR SIMILAR ARTICLE

Shigeru Masuda, Fort Lee, N.J., assignor to Noritake Co., Inc., New York, N.Y., a corporation of New York

Filed May 16, 1966, Ser. No. 2,322

Term of patent 7 years

(Cl. D44—15)

The figure is a plan view of a plate or similar article showing my new design.

The plate is of a conventional configuration when viewed from the side and bottom thereof.

I claim:

The ornamental design for a plate or similar article, substantially as shown and described.
